UNITED STATES PATENT OFFICE.

ROY ROGERS AND MILE GROVES, OF MIDIAN, KANSAS.

STUFFING-BOX.

1,400,991.

Specification of Letters Patent. Patented Dec. 20, 1921.

Application filed November 4, 1920. Serial No. 421,794.

To all whom it may concern:

Be it known that we, ROY ROGERS and MILE GROVES, citizens of the United States, residing at Midian, in the county of Butler 5 and State of Kansas, have invented certain new and useful Improvements in a Stuffing-Box, of which the following is a specification.

This invention relates to improvements in 10 stuffing boxes, more particularly to devices of this character employed in deep well operations for packing the polish rods of pumps thus used, and has for one of its objects to improve and simplify the construction and increase the efficiency and utility of devices of this character.

Another object of the invention is to provide a device of this character in which provision is made for removing and inserting 20 the polish rod without detaching the body of the stuffing box.

Another object of the invention is to provide a device of this character in which provision is made for controlling pressure upon 25 the packing gland, for instance to stop leakage, without removing any of the parts or stopping the motion of the polish rod.

With these and other objects in view, the invention consists in certain novel features 30 of construction as hereinafter shown and described and specifically pointed out in the claims, and in the drawings illustrative of the preferred embodiment of the invention.

Figure 1 is a plan view of the follower 35 gland.

Fig. 2 represents the follower gland in longitudinal section.

Fig. 3 represents the body or bell nipple part of the device.

Fig. 4 is a plan view of the portion shown in Fig. 3.

Fig. 5 is a transverse section of the ring follower member.

Fig. 6 is a plan view of the ring follower 45 member.

Fig. 7 is a longitudinal section of the supporting body and follower gland assembled.

Fig. 8 is a detached perspective view of the weight carrying lever.

Fig. 9 is a view of the supporting link.

Fig. 10 is a detached perspective view of the weight carrying box.

Fig. 11 is a detached perspective view of the weight box strap.

Fig. 12 is a perspective view of the device assembled.

Fig. 13 is a sectional view on a reduced scale, of the improved device.

The improved device comprises a hollow body or shell portion, commonly called a bell nipple, represented as a whole at 10, and reduced at the lower end and threaded externally to enable it to be attached to a coupling 11, as shown in Fig. 13, the latter uniting the main pump tube 12 and lateral discharge 13.

The shell 10 is formed with an internal shoulder 14 to support a follower ring 15 and bearing upon the follower ring are a plurality of packing rings 16 of rubber or other suitable material.

The gland member of the device is represented as a whole at 17 and fits closely within the shell 10 and bears at its inner end upon the outermost packing ring 16.

At its upper end the gland 17 is enlarged at two opposite sides as shown at 18 and the upper faces of the enlargement notched, as shown at 19.

A pressure applying lever forms a part 20 of the invention and is formed with two side portions 20-21 united into a single hook 22 at one end and with spaced hooks 23-24 at the other ends.

The lever members diverge from the single terminal hook 22 to the spaced terminal hooks 23 and 24, and engage loosely by the spaced sides in the notches 19 of the gland, as shown.

A link formed of a body portion 25 having a triangular loop at one end to engage in the hooks 23 and 24 and an eye, 27 to engage the lateral discharge branch 13, serves as an adjustable fulcrum to the lever 20-21.

Suspended by a loop or strap 28 from the single hook 22 is a receptacle 29 of suitable size to receive any convenient weight material such as earth, stones, scrap metal, or the like.

A strap or link 30 is preferably located on the two part lever to prevent them from being displaced laterally and thus being disconnected from the notches 19.

By this simple arrangement the requisite pressure can be applied to the gland member 17 to compress the yieldable packing rings 16 against the polish rod, a portion of which is represented at 31, and produce the requisite liquid tight packing to the rod, while at the same time the pressure may be readily and quickly increased in event of leakage caused by the wear of the packing.

rings or from other causes, by shifting the link member 25 along the discharge member 13 and correspondingly shifting the lever members 20-21 in the notches 19 to increase the strength of the leverage force, and without removing any of the parts or stopping the motion of the polish rod.

The preferred embodiment of the invention is disclosed in the drawings and set forth in the specification, but it will be understood that any modifications within the scope of the claimed invention may be made in the construction without departing from the principle of the invention or sacrificing any of its advantages.

What we claim is:

1. A device of the class described associated with a well tube and its polish rod and discharge branch and comprising a tubular body adapted to be attached to the well tube, a packing gland engaging in said tubular body and adapted to compress packing rings against the polish rod, said gland having upwardly opening notches, a lever device including spaced side members bearing

loosely in said notches, and adapted to support a weight device at its longer end, and a link engaging the two part lever at the other end, and slidably engaging the discharge branch.

2. A device of the class described associated with a well tube and its polish rod and discharge branch comprising a tubular body adapted to be attached to the well tube, a packing gland engaging in said tubular body and adapted to compress packing rings against the polish rod, said gland having upwardly opening notches, a lever device including spaced side members bearing loosely in said notches, united in a single hook at one end and with spaced hooks at the other ends, said single hook adapted to support a weight device, and a link having a loop at one end engaging the spaced hooks of the lever and slidably engaging the discharge branch by its other end.

In testimony whereof, we affix our signatures hereto.

ROY ROGERS.
MILE GROVES.
